UNITED STATES PATENT OFFICE.

ABNER W. BISHOP, OF RACINE, WISCONSIN.

FINGER-GRIP FOR FISHING-RODS.

No. 802,027.

Specification of Letters Patent.

Patented Oct. 17, 1905.

Application filed May 9, 1905. Serial No. 269,527.

To all whom it may concern:

Be it known that I, ABNER W. BISHOP, a citizen of the United States, residing at Racine, in the county of Racine and State of Wisconsin, have invented certain new and useful Improvements in Finger-Grips for Fishing-Rods; and I do declare the following to be a full, clear, and exact description of the invention, such as will enable others skilled in the art to which it appertains to make and use the same.

My invention relates to improvements in finger-grips for fishing-rods; and it consists in the novel construction, combination, and arrangement of devices herein shown and described.

The object of the invention is to provide a simple, strong, and rigid finger-grip of this character which may be quickly and easily applied to and adjusted upon fishing-rods of any kind and size and which when not in use may be folded over to permit the rod to be inserted in its casing or holder.

The above and other objects which will appear as the nature of my invention is better understood are accomplished by means of the construction illustrated in the accompanying drawings, in which—

Figure 1 is a side elevation of the handle-section of a fishing-rod, showing my improved finger-grip applied thereto, the same being shown in its operative position in full lines and in its folded position in dotted lines. Fig. 2 is a transverse sectional view taken on the line 2 2 in Fig. 1, and Fig. 3 is a perspective view of the finger-grip removed from the rod.

Referring to the drawings by numeral, 1 denotes a portion of the handle-section or other section of a fishing-rod, and 2 denotes my improved finger-grip which is adjustably mounted thereon. The grip consists of a yoke or clip 3, a screw-bolt or similar clamping element 4, and a finger-hook 5. The yoke 3 is adapted to surround or engage the rod 1 or the reel-seat 6 upon the latter and is formed in its arms 7 with apertures 8, through which the bolt 4 passes. I preferably construct this clamping-yoke 3 from a single piece of metal of either round or square stock by bending the same as shown. I also preferably construct the hook 5 from similar material by bending a single piece upon itself at its center to form the finger-engaging portion 9 and

then bending its ends to form eyes 10, through which the bolt 4 passes. The latter is preferably in the form of a screw-bolt having a head 11 at one end and a nut 12 at its opposite screw-threaded end.

The use and advantages of the invention will be readily understood. It will be seen that the clamp formed by the yoke 3 and bolt 4 is adapted for engagement with rods of various sizes and may be quickly adjusted and secured upon any portion of the rod. When the yoke 3 is engaged with the reel-seat 6, as shown in Fig. 1 of the drawings, the latter will be held securely upon the rod. By pivotally mounting the hook 5 upon the bolt 4 it will be seen that it may be folded over upon the rod, as shown by the dotted lines in Fig. 1, when it is desired to insert the rod in its case or holder.

While I have shown and described the preferred embodiment of my invention, it will be understood that I do not wish to be limited to the precise construction herein set forth, since various changes in the form, proportion, and the minor details of construction may be resorted to without departing from the principle or sacrificing any of the advantages of this invention.

Having thus described my invention, what I claim as new, and desire to secure by Letters Patent, is—

1. A finger-grip for fishing-rods comprising an adjustable clamp and a hook thereon.
2. A finger-grip for fishing-rods comprising an adjustable clamp and a hook pivotally mounted thereon.
3. A finger-grip for fishing-rods having a pivotally-mounted hook.
4. A finger-grip for fishing-rods having a folded hook.
5. A finger-grip for fishing-rods comprising a yoke or clip, a clamping element therefor, and a hook pivoted upon said element.
6. A finger-grip for fishing-rods comprising a yoke or clip, a clamping element engaged with the arms of the same, and a swinging hook.
7. A finger-grip for fishing-rods comprising a yoke or clip, a clamping-bolt passed through the arms of said yoke or clip, and a hook upon said bolt.
8. A finger-grip for fishing-rods comprising

ing a yoke or clip having apertured arms, a hook having an apertured end, and a clamping screw-bolt passed through the apertures in said yoke or clip and said hook to bind the 5 arms of said yoke upon the object with which the latter is engaged and to pivotally mount said hook, substantially as described.

In testimony whereof I have hereunto set my hand in presence of two subscribing witnesses.

ABNER W. BISHOP.
